UNITED STATES PATENT OFFICE.

AXEL FRITZ, OF EVERETT, MASSACHUSETTS.

CATTLE-STANCHION.

1,217,434.

Specification of Letters Patent. Patented Feb. 27, 1917.

Application filed April 3, 1916. Serial No. 88,463.

To all whom it may concern:

Be it known that I, AXEL FRITZ, a citizen of the United States, residing at Everett, in the county of Middlesex and State of Massachusetts, have invented new and useful Improvements in Cattle-Stanchions, of which the following is a specification.

This invention relates to improvements in cattle stanchions.

10 The object of the invention is to provide a stanchion of great strength and durability which is pivotally mounted so as to permit the cattle detained thereby to have free and practically unlimited movement so far as the 15 swinging of their heads is concerned.

Another object of the invention is to provide means adapted to be operated to simultaneously operate a number of stanchions so as to release the cattle held or detained 20 thereby.

Still another object of the invention is to provide means for simultaneously closing a plurality of the stanchions after the cattle have been allowed to enter their respective 25 stanchions to secure said cattle in place between the side bars thereof.

Still another object of the invention is to provide means for rendering any predetermined stanchion inoperative in so far as the 30 common operating or releasing means is concerned.

Still another object of the invention is to provide means for adjustably supporting the head pieces of the several stanchions so as 35 to remove the weight thereof from the common actuator for releasing and locking the side bars of the several stanchions.

The invention consists in the combination and arrangement of parts whereby the above 40 objects and certain other objects hereinafter appearing may be obtained, as set forth in the following specification and particularly pointed out in the claims.

Referring to the drawings:

45 Figure 1 is a front elevation of a pair of stanchions embodying my invention with the side bars of both stanchions shown contracted.

Fig. 2 is a front elevation of one of the 50 stanchions embodying my invention, the side bars thereof shown separated.

Fig. 3 is a detailed front elevation of the head piece of a stanchion illustrating another type of means for pivotally supporting said head piece.

Fig. 4 is a longitudinal section through

the head piece of the form shown in Figs. 1 and 2.

Fig. 5 is a transverse section taken substantially on the line 5—5 of Fig. 4. 60

Fig. 6 is a detailed section taken on the line 6—6 of Fig. 1.

Fig. 7 is a section taken on the line 7—7 of Fig. 5.

Fig. 8 is a section taken on the line 8—8 65 of Fig. 4, illustrating the connection between one of the side bars and the head piece.

Fig. 9 is a section taken on the line 9—9 of Fig. 1.

Fig. 10 is a transverse section taken on the 70 line 10—10 of Fig. 4.

Like numerals refer to like parts throughout the several views of the drawings.

In the drawings, 11, 11 represent the usual upright supports which separate one stanchion from another when a number of stanchions are arranged in a row. Each 75 separate stall preferably has two such supports and these are placed at such distances apart as to supply sufficient space for the 80 cattle, the arrangement thereof being such that a wide space 12 is provided, suitable to contain the usual side members for securing or detaining the cattle within their respective stalls and with room enough left between said side members and said upright supports to permit said side members to be 85 opened, that is, separated.

The upright supports 11 for one stall are arranged as close to the upright supports 90 for the next or adjacent stall as will be permissible to provide sufficient room for the cattle without interfering with each other. In the present case the space left is indicated at 13, this space being much less than the 95 space 12. The upright supports 11 are positioned in different ways, in the present case, however, tie rods 14 and 15 are interposed between the supports 11 in the space 13 while another tie rod 16 extends from the 100 top of one of said uprights to the top of the next upright. The lower ends of the supports 11 are secured in any suitable manner to the floor 17 of the stable.

A cross-head or truss 18 is arranged between the upright members 11 of each stanchion or stall spanning the gap or space 12 and thus completes the supports for said uprights and cooperates with the tie piece 16 to properly position all of said uprights. The 110 cross heads 18 are preferably bent upwardly at the center to form trusses and from each

of said cross-heads is suspended an adjustable support 19, including a screw 20 engaging the cross-head 18 and a yoke 21. A head piece 22 is suspended from the yoke 21 in any suitable manner preferably by a pair of chains 23 which extend from a common link 24 attached to said yoke to the head piece 22 at points 25, 25 upon opposite sides of the center of said head piece which 5 center corresponds with the axis of the screw 20, said chains being preferably attached to said head piece by rivets 26. The head piece 22 preferably embodies in its construction a U-shaped member or channel bar 10 arranged horizontally, the lower ends of the chains 23 being arranged between the sides of said channel. The arrangement of the chains 23 permits said head piece to be swung about a vertical axis.

15 A pair of links 27 is pivoted to said head piece 22 one adjacent to each end thereof, preferably by pins 28, extending from one side of the channel to the other. The links 27 are adapted to be swung about pivots 28 from an upright position, as illustrated in Figs. 1 and 4, to an inclined position, as illustrated in Fig. 2. A stop 29 is formed upon each of the links 27 and adjacent to the ends thereof engaging the pivots 28, said 20 stops being arranged to extend downwardly through openings 30 in a part of the U-shaped head piece 22 so as to engage the under face thereof when said links are in their inclined positions.

25 A portion 31 of each link at this time rests upon the upper face 32 of said head piece and upon the opposite side of the pin 28 from the stop 29, said contacting surface and said stop being arranged to sustain the 30 weight of the link and the members suspended therefrom when said link is in its inclined position, thus removing the weight from the pin 28. From each of the links 27 is suspended a side bar 33, the upper end of 35 said side bar being forked at 34 to engage opposite faces of the link 27 adjacent to the outer end thereof at which point said link and said side bar are pivotally connected together by a pin 35. The lower ends 36 of 40 the side bars 33 pivotally engage a separator 37 connected at a point midway between said side bars by a chain 38 with an eye 39 attached to the floor 17.

45 The side bars 33 are formed preferably of wood 40 bound upon opposite faces by convexly formed metal strips 41 which are much narrower than the wood section 40. A portion of the wood 40 extends inwardly at 42 beyond the edges of the metal strips 41 to engage the neck of the animal which is detained by the side bars. The arrangement of the links 27 with respect to the separator 37 permits the side bars to be moved laterally toward or away from each other to 50 contract or separate the same. When said

bars are in their contracted positions, as shown in Fig. 1, the animal will be detained therebetween, but when in their separated positions, as illustrated in Fig. 2, the animal 5 will be freed.

70 It is necessary that the side bars 33, 33 be locked to the head piece when the same are in their upright positions, as illustrated in Fig. 1, so as to detain the cattle therein. To accomplish this result a locking member 75 or bar 43 is provided. This bar is preferably superimposed on said head piece and adapted to be moved vertically with respect thereto to unlock or lock said side bars. Guides 44, 44, preferably formed upon said locking bar, are arranged to project downwardly between the sides of the U-shaped member 22 so as to prevent said locking member 80 from moving out of alignment with said head piece when the same is moved vertically thereon.

85 Loops 45, 45, preferably attached to the member 22 and extending upwardly therefrom, engage a cross rib 46 and thus limit the upward movements of said locking bar 90 to prevent the guides 44 from being disengaged from said head piece. The opposite ends of said locking bar are forked at 47 and upon the inner faces of the same are provided hooks 48 constructed and arranged 95 to coöperate with projections 49, preferably formed upon the members constituting the forked end 34 of the side bars 33 when said side bars are in their upright positions to lock the same against relative movement.

100 The stanchions embodying my invention are particularly adapted to be arranged in series and operated simultaneously to release the cattle therefrom, thus in case of a fire or any other accident which might necessitate 105 the freeing of the cattle a single operation from one end or the other of the series of stanchions will suffice to release the entire number. To accomplish this result the locking bar 43 has attached thereto preferably 110 adjacent opposite ends, flexible means, such as chains, 50, 50 which extend upwardly and engage a rotary member or preferably a hollow shaft 51, common to each stanchion of the series and rotatably mounted in bearings 52, 52, one of said bearings being secured to the top of each of the upright supports 11. The chains 50, 50 preferably have hooks 53 at their upper ends adapted to be hooked into eyes 54, permitting the hooks of 115 any particular stanchion to be detached from said shaft when it is desired that said stanchion shall remain locked while the others are being unlocked by the shaft.

120 The shaft 51 is arranged to extend through 125 the yoke 21 said yoke being split at 55 into two parts connected together by screws 56. The opening 57 through the yoke is substantially larger than the shaft and permits said yoke to be moved up or down a limited 130

amount without touching said shaft. In this way the entire weight of the stanchion will be supported by the truss 18 and not by said shaft, permitting said shaft to rotate more freely than would be the case were it supporting the entire weight of the stanchion.

The eyes 54 to which the chains 50 are attached are constructed in the form of staples, the arms of which pass upwardly through the shaft and are attached thereto by nuts 71. One arm of said staple, preferably the arm nearer to the yoke 21, extends upwardly a considerable distance beyond the arm which is engaged by the nut 71. This arm 58 is adapted to engage said yoke during the rotation of the shaft, and assists in positioning the shaft and yoke relatively to each other. The rotation of the shaft 51 in one direction is adapted to wind the chains 50, 50 thereon and thus cause the locking bar 43 to be elevated, whereupon the hooks 48 will be disengaged from the projection 49 and the side bars freed from the head piece. To insure the separating of said side bars upon their being released by the locking bar the axes of the pivots 28 are arranged closer together than are the axes of the pivots 35, especially when the links and side bars are in their contracted positions, thus the weight of said side bars will have a tendency to separate said bars immediately upon the unlocking thereof by the locking bar 43 and cause the same to separate until further outward movement is prevented by the stops 29 and the portion 31 of the links engaging the upper surface 32 of the channel.

It is often desirable that the side bars be so arranged as to be closed simultaneously from one end or the other of the row of stanchions and to accomplish this result flexible means have been provided for operatively connecting the upper ends of the side bars with the shaft 51. These means preferably consist of chains 59 attached to extensions 60 formed upon the links 27, and also to the eyes 54 said chains being arranged to be wound upon the shaft 51 when the same is rotated in the opposite direction to that which winds the chains 50 thereon, to contract said side bars and thus draw them into the jaws or forked ends of the locking bar 43 and into engagement with the hooks 48 which are rounded or inclined upon the outer ends 61 so as to permit the projections 49 to pass to the inner ends thereof.

Collars 62 are placed upon the shaft 51 and assist in guiding the chains 59 while the same are being wound upon said shaft. The opposite ends of the head piece 22 are slightly tapered at 63 so that in case the connections between the side bars 33, links 27 and head piece 22 become somewhat loosened by wear and should not properly aline when being contracted, the rounded or tapered

ends of said head piece will properly guide the forked ends of said side pieces between the arms of the forked ends of said locking member.

The shaft 51 is usually at a substantial distance above the floor and out of the reach of the attendant and to enable the same to be operated easily from the floor operating means have been provided, preferably consisting of a sprocket 64 fast to the shaft 51 and connected by a chain 65 to a sprocket 66 rotatably mounted in a convenient location, preferably on one of the upright members 11, said sprocket 66 being provided with means whereby the same may be rotated, 80 such as a crank 67.

Fig. 3 illustrates another method of securing the head piece to the yoke in which case the head piece 22' is mounted thereon a hanger 68 having jaws 69 adapted to receive the lower link of a chain 70, said chain being arranged to engage the link 24, as shown in Fig. 1, and adapted to take the place of the two chains 23 shown therein. The remaining features of this structure are identical 90 with the form illustrated in Fig. 1.

The operation of the stanchion is as follows:

When it is desired to release the entire herd of cattle detained by the several stanchions of the series the operator rotates the sprocket 66 by means of the crank 67 which, through the chain 65 and sprocket 64, imparts a rotary motion to the shaft 51. The chains connected to the shaft 51 will, 100 previous to said rotation, occupy the positions shown in Fig. 1, but upon the rotation of the shaft 51 in the direction of the arrow *a* the chains 59 will be unwound from said shaft and the chains 50 wound thereon. 105

When this occurs the locking member or bar 43 will be raised and the side bars released, permitting said side bars to separate to the positions shown in Fig. 2, whereupon the cattle detained thereby will be released 110 and permitted to pass therefrom. If it is not desired to release all of the cattle at this time, before the shaft is rotated in the direction of the arrow *a* the chains 50 of any particular stanchion may be unhooked from the 115 eyes 54 and in consequence thereof said locking bar will not be raised.

After the cattle are driven into their respective stalls and it is desired to contract the side bars of the series the shaft 51 must 120 be rotated in the opposite direction to that indicated by the arrow *a* so as to wind the chains 59 upon said shaft and unwind the chains 50 therefrom. In this manner the side bars will be drawn upwardly into the 125 forked ends of the locking member which is gradually lowered by the chains 50 and automatically locked by the hooks 48 engaging the projections 49.

Having thus specifically described my in- 130

vention what I claim and desire by Letters Patent to secure is:

1. A cattle stanchion having, in combination, a horizontally disposed channel bar constituting a head piece, the flanges of said bar extending upwardly, a pair of links pivoted upon said head piece between said flanges, a pair of side bars pivotally suspended from said links adapted to be moved laterally with respect to each other to separate or contract said side bars, means to lock said side bars to said head piece in their contracted positions, a rotatable member mounted above said head piece, and means operatively connecting said locking means with said rotatable member adapted to operate said locking means to release said side bars.
2. A cattle stanchion having, in combination, a head piece, a pair of side bars, links adapted to suspend said side bars from said head piece either in contracted or separated relation, a rotary member, means for operatively connecting the upper ends of said side bars with said rotary member and adapted to be operated by said rotary member to contract said side bars, means for locking said side bars contracted, and means detachably connected with said rotary member adapted to be operated thereby to move said locking means and release said side bars.
3. A cattle stanchion having, in combination, a head piece, a pair of links pivoted respectively at their lower ends adjacent to opposite ends of said head piece, a pair of side bars pivoted respectively to the upper ends of said links, a separator for the lower ends of said side bars, a locking member on said head piece adapted to lock said side bars in contracted relation, and means for operating said locking means to simultaneously release said side bars.
4. A cattle stanchion having, in combination, a head piece, a pair of links pivoted respectively adjacent to opposite ends of said head piece, a pair of side bars pivoted respectively to the outer ends of said links, a separator for the lower ends of said side bars, a locking bar superimposed on said head piece, means on opposite ends of said bar adapted to interlock with said side bars and retain the same contracted, and means constructed and arranged to operate said locking bar to release said side bars.
5. A cattle stanchion having, in combination, a head piece, a pair of links pivoted respectively adjacent to opposite ends of said head piece, a pair of side bars pivoted respectively to the outer ends of said links, a separator for the lower ends of said side bars, a rotary member, flexible means operatively connecting said rotary member with the outer ends of said links with respect to said head piece adapted to be wound upon said rotary member during the rotation thereof in one direction and to contract said

side bars, means for locking said side bars in their contracted relation, and flexible instrumentalities operatively connecting said locking means with said rotary member, adapted to be operated by said rotary member during the rotation thereof in the opposite direction to release said side bars.

6. A cattle stanchion having, in combination, a head piece, a pair of links pivoted respectively adjacent to opposite ends of said head piece, a pair of side bars pivoted respectively to the outer ends of said links, a separator for the lower ends of said side bars, the axes for the pivots connecting said links with said head piece being below and the distance therebetween less than the distance between the axes of the pivots for connecting said links with said side bars when said side bars are contracted, whereby the weight of said side bars will have a tendency to separate the same, and means for locking said side bars contracted.

7. A cattle stanchion having, in combination, a head piece, a pair of links pivoted respectively adjacent to opposite ends of said head piece, a pair of side bars pivoted respectively to the outer ends of said links, a separator for the lower ends of said side bars, means on said links adapted to engage said head piece and limit the movements of said side bars outwardly with respect to said head piece, a locking bar on said head piece adapted to limit the movements of said side bars toward said head piece, means on said locking bar adapted to interlock with said side bars to lock said bars contracted, and means adapted to be moved in one direction to release said side bars and in the opposite direction to contract said side bars.

8. A cattle stanchion having, in combination, a head piece, a pair of links pivoted respectively adjacent to opposite ends of said head piece, a pair of side bars pivoted respectively to the outer ends of said links, a separator for the lower ends of said side bars, the distance between the axes of the pivots connecting said links with said head piece being less than the distance between the axes of the pivots for connecting said links with said side bars when said side bars are contracted, whereby the weight of said side bars will have a tendency to separate the same, a locking bar superimposed on said head piece, means on opposite ends of said bar adapted to interlock with said side bars and retain the same contracted, and means constructed and arranged to operate said locking bar to release said side bars.

9. A cattle stanchion having, in combination, a head piece, a pair of links pivoted respectively adjacent to opposite ends of said head piece, a pair of side bars pivoted respectively to the outer ends of said links, a separator for the lower ends of said side bars, a rotary member, flexible means operatively connecting said rotary member with the outer ends of said links adapted to be operated by the rotation of said rotary member to contract said side bars.

- bars, the distance between the axes of the pivots connecting said links with said head piece being less than the distance between the axes of the pivots for connecting said links with said side bars when said side bars are contracted, whereby the weight of said side bars will have a tendency to separate the same, a rotary member arranged above said head piece, flexible means operatively connecting said rotary member with the outer ends of said links adapted to be operated by the rotation of said rotary member to contract said side bars, and means for locking said side bars contracted.
- 10 15 20 25 30 35 40 45 50 55 60 65 70
10. A cattle stanchion having, in combination, a pair of supporting members, a cross head connecting said supporting members together, a head piece, an adjustable support adapted to suspend said head piece from said cross head, said support including a yoke, a shaft rotatably mounted on said supporting members extending through said yoke and adapted to be rotated independently thereof, a pair of side bars suspended from said head piece and movable laterally relatively to each other, flexible means operatively connecting said side bars with said shaft adapted to be operated by the rotation of said shaft to contract said side bars, and means for locking said side bars contracted.
11. A cattle stanchion having, in combination, a horizontally disposed channel bar constituting a head piece, a pair of links pivoted respectively at distances from opposite ends of said channel bar and between the flanges of said bar, said links being con-

structed and arranged to swing from upright to substantially horizontal positions against the web of said channel bar, a pair 40 of side bars pivoted respectively to the free ends of said links, the ends of said side bars being forked to engage opposite faces of said links and receive the ends of said channel bar when said links are in their upright positions and said side bars are contracted, means for locking said side bars contracted, and means for simultaneously releasing said side bars.

12. A cattle stanchion having, in combination, a pair of supports, a truss extending from one of said supports to the other, a pivotal head piece, means for adjustably suspending said head piece from said truss, a pair of side bars suspended from said head piece adapted to be moved laterally relatively to each other to separate and contract said bars, means for locking said bars contracted, a shaft rotatably arranged above said head piece on said supports and extending through said head piece suspending means adapted to prevent the rotation of said means, means operated by said shaft adapted to move said locking means to release said side bars, and means operated by said shaft adapted to contract said side bars.

In testimony whereof I have hereunto set my hand in presence of two subscribing witnesses.

AXEL FRITZ.
